UNITED STATES PATENT OFFICE.

ADOLPH W. SCHRAMM, OF RIVERTON, NEW JERSEY.

ANTENNA CONSTRUCTION FOR AERIAL VESSELS.

1,307,155.

Specification of Letters Patent. Patented June 17, 1919.

Application filed April 9, 1918. Serial No. 227,529.

To all whom it may concern:

Be it known that I, ADOLPH W. SCHRAMM, a citizen of the United States, residing in Riverton, New Jersey, have invented certain 5 Improvements in Antenna Construction for Aerial Vessels, of which the following is a specification.

The wireless telegraph apparatus for use on the various forms of aircraft usually includes a device for paying out and reeling in a long wire or cable constituting an antenna and, as customarily constructed, this has been found to be seriously defective owing to the frequent breakage of the wire due to 10 the sudden pull exerted upon it by its weight and the weight on its free end when all of said wire has been paid out. While braking devices have been employed for enabling the operator to regulate the speed at which the 15 wire was delivered from the reel on which it was wound, these at best were uncertain in operation and unsatisfactory because of the attention they required.

One object of my invention therefore, is 20 to provide a novel combination of apparatus including a reel particularly designed for the reception of the antenna wire of a wireless telegraph outfit such as is carried by an aeroplane for example, which shall possess 25 means for automatically regulating the speed at which the weighted wire is delivered after having been released, so that the shock or tension exerted upon the wire by its weight and by the weight on its free end 30 after it has been fully paid out while the aeroplane is flying shall be so reduced as to be insufficient to cause breakage of said wire even though this possesses but relatively low tensile strength, as is required.

40 These objects and other advantageous ends I attain as hereinafter set forth, reference being had to the accompanying drawings, in which—

Figure 1 is a front elevation of a reel constructed according to my invention;

Fig. 2 is a vertical section on the line 2—2, Fig. 1;

Figs. 3 and 4 are vertical sections on the lines 3—3 and 4—4 Fig. 2, the spool being 50 omitted;

Fig. 5 is a fragmentary section showing the operating handle in its two extreme positions.

Fig. 6 is an elevation, to some extent dia-

grammatic, showing the parts constituting 55 my invention; and

Fig. 7 is an elevation of a portion of the apparatus shown in Fig. 6, illustrating it on an enlarged scale.

In the above drawings, 1 represents a flat 60 metal plate having a generally circular form and provided with a suitable number of projecting lugs 2 formed with holes for the reception of bolts or screws whereby the device may be fixed to a supporting structure, 65 such as the aeroplane 52, Figs. 6 and 7.

Riveted or otherwise rigidly and permanently secured to this plate 1 is a flat drum 3 preferably made of relatively thin, strong, pressed metal having in its flat face a number of struck up teeth 4 constituting a ratchet. Centrally mounted and rigidly fixed in the plate 1 is a relatively heavy, substantial stud or short spindle 5 constituting a journal on which is rotatably mounted a 70 sleeve or collar 6, projecting from and centrally mounted in a second metal plate 7 which with it is held on said journal 5 by a flat washer 8 retained on the outer end of the spindle by a screw 9.

The plate 7 which extends over and closes the open face of the drum 3, has mounted upon its inner face a pair of flat segmental weights 10 movably connected to said plate by pivots 11 and normally drawn toward the central sleeve 6 by coil springs 12, each of which extends between a pin 13 projecting inwardly from the face of the plate 7 and an eye 14 on the weight. Each of the latter has set in its outer and preferably circularly 85 curved edge a shoe 15 of leather or other suitable material having a high coefficient of friction and designed to coact with the inner cylindrical surface of the drum 3 when the weight has swung outwardly to a predetermined extent against the action of the spring 12.

The plate 7 also carries a dog in the shape of a longitudinally movable plunger 16 guided in a sleeve 17 fixed to and projecting 100 inwardly from the plate 7 at a distance from the center of the spindle 5 equal to the radius of the circle on which the ratchet teeth 4 are formed. This plunger at all times tends to move inwardly into engagement 105 with said ratchet teeth under the action of a coil spring 18 operative between its inner head and a shoulder formed within the

sleeve 17 so as to permit rotation of the plate 7 in one direction, but it may be forcibly drawn out against the action of this spring by means of a lifting device provided by a 5 rotatable disk 19 having an operating arm 20 and provided with a raising cam 21 placed on its edge in such a position as to extend under a collar 22 pinned to the outer end of said plunger 16 so as to constitute its 10 second or outer head. The arrangement of these parts is such that when the operating arm 20 occupies the position shown in dotted lines in Fig. 1, the spring 18 holds the plunger in engagement with the ratchet 15 teeth 4, while the act of moving said arm into the position shown in full lines Fig. 1, turns the disk 19 sufficiently to cause its edge cam 21 to so act on the outer head 22 of the plunger 16 as to move it outwardly, free of 20 the ratchet teeth 4. The disk 19 is pivotally held to the plate 7 by a rivet 24, between whose head and said disk is confined a spring washer 25 which exerts sufficient friction on the latter to retain it in any 25 given position.

The spool 26 for the antenna wire consists of two annular flanged pieces of sheet material 27 having parallel, radially extending webs 28 riveted, spot welded, or otherwise 30 permanently connected to form a receptacle for said wire and including any desired number of inwardly projecting portions 29 formed with side notches for the reception of the bodies of a similar number of rivets 35 or other headed members 30 which project from the outer face of the plate 7;—the arrangement being such that the web portions 28 of the spool may be laid parallel and in contact with the outer face of said 40 plate 7 concentrically with the spindle 5 and thereafter given a small rotary movement, causing the side recesses of the projections 29 to receive the rivets 30 whose heads then act to hold the spool to said plate against 45 sidewise removal. In order to removably retain said spool in this position I mount a spring-pressed locking plunger 32 in a sleeve or bushing 32^a mounted in the plate 7 in such position that when the lugs or projections 50 29 engage the headed members 30 as shown in Fig. 1, said plunger is free to be automatically projected behind one of said extensions and is thereby caused to retain the spool attached to the plate 7 with no 55 possibility of becoming accidentally separated therefrom.

For turning the plate 7 with the spool on the spindle 5, I provide a handle 36 pivoted to said plate at 37 so that it may move in a 60 plane at right angles to the plate and to one side of the center line thereof. The stem of this handle is preferably provided with a right angle extension 39 formed by bending it upon itself so that when it is turned 65 on its pivot 37 into an inactive position prac-

tically within the cylindrical recess provided by the spool 26, this projection will extend outwardly where it may be easily struck by the hand of the operator when it is desired to quickly move the main handle 70 from its folded to its extended position. This secondary handle or projection 39 is so placed as to strike the side of the spool and limit the outward swing of the handle stem. A flat spring 40, fixed at one end to 75 the plate 7, extends over a knife edge or tapered pin 41 fixed to the pivot 37 in such position that it tends to move the handle from a mid or neutral position into either of its extreme positions shown in Fig. 5. 80

Under conditions of use a length of wire 50 constituting an antenna has one end permanently fixed to the spool 26 in any desired manner and is wound within the cavity thereof with a suitable weight 51 attached 85 to its outer end. The filled spool may be attached to the plate 7 by placing it over the same with its inward extensions 29 adjacent the headed members 30 and thereafter giving it a slight turning motion sufficient 90 to bring the walls of the side recesses of its extensions 29 into engagement with the bodies of said members, whereupon the spring plunger 32 automatically locks it in place. 95

Normally the plate 7 with its attached spool and regulating weights is held from turning on the spindle 5 by the dog 16 which engages the teeth 4 of the fixed drum and when it is desired to pay out the antenna 100 wire, the disk 19 is turned from the position shown in dotted lines in Fig. 1 to that shown in full lines so that its cam 21 raises the plunger 16 out of the path of the ratchet teeth 4 and retains it in this raised position. 105 Under the action of the weight 51 on the end of the wire 50, this is now drawn off of the spool which, with the plate 7 and weights 10, rotates at an increasing speed until by reason of the centrifugal force acting on the 110 weights, these swing outwardly against their springs 12 and move their shoes 15 into frictional engagement with the inner surface of the fixed drum. It is noted that the weights and shoes are so mounted on the plate 7 115 that the friction between the drum and shoes tends to swing said weights outwardly and therefore aids the centrifugal force in applying a braking force to the rotating plate 7 and its attached spool. 120

By reason of the construction described and shown, this braking force is gradually applied so that the rate of delivery of the weighted wire is limited to such a point that when all of said wire has been finally paid out, there is no such sudden tensile stress due to the inertia of said wire and weight as would cause the wire to break, even though it be made of comparatively weak material in order to prevent injury to the aeroplane 130

52 in case of its becoming accidentally entangled with some fixed structure.

When it is desired to draw in the wire, the handle may be moved from its folded position shown in Fig. 5 by the operator striking its projecting portion 39 in a line parallel with the plane of the plate 7, as a result of which the handle moves from the position shown in full lines in Fig. 5 to that shown 10 in dotted lines. Its main portion may now be grasped by the operator and the plate 7, with the spool, turned to wind up the antenna wire.

Under ordinary conditions the arm 20 of 15 the disk 19 is so turned as to permit the plunger or dog 16 moving toward the fixed plate 1 into the path of the ratchet teeth, so that as the spool is turned said plunger rides successively over said teeth. In case 20 the handle should be released at any time the plunger is at once engaged by one of the ratchet teeth as the spool tends to turn under the action of the weighted wire so that unwinding of the latter is prevented.

25 With the arrangement of parts shown, a spool and its wire may with the utmost ease be removed from the plate 7 and replaced by another spool with its associated antenna, since for this purpose it is merely necessary 30 to depress the locking plunger or pin sufficiently to permit such slight turning of the spool as will allow of the inward projections 29 moving free of the headed members 30, whereupon said spool may be moved laterally away from said plate.

I claim:

1. The combination of an aerial vessel; a reel mounted thereon; a flexible member having one end connected to the reel; a 40 weight on the other end of said member; and means for automatically limiting the speed of delivery of the flexible member from the reel to an amount insufficient to cause break-

age of said member when it has all been paid out while said vessel is moving in a generally horizontal direction.

2. The combination of an aerial vessel; a reel mounted thereon; a flexible weighted member having one end connected to the reel and free to assume a curved outline when delivered from the reel while the vessel is moving in a generally horizontal direction; and means for automatically preventing the force of inertia of the member exceeding its breaking strength at the time it has all been 55 paid out.

3. The combination of an aerial vessel; a reel mounted thereon; a flexible weighted member having one end connected to the reel and free to assume a curved outline when delivered therefrom while the vessel is being moved in a generally horizontal direction; and a centrifugal braking device set to automatically limit the speed of delivery 60 of the member to an amount which will prevent the force of its inertia exceeding its breaking strength at the time it has all been paid out from the reel.

4. The combination in an aerial vessel including a member having a series of ratchet teeth; a structure including a spool rotatably mounted on said member; a flexible weighted member connected to said spool at one end and free to assume a curved outline when delivered therefrom while the vessel is moving in a generally horizontal direction; means for automatically preventing the force of inertia of the member exceeding its breaking strength when it has all been paid out from the spool; a dog mounted on the 70 rotatable structure in position to coact with the ratchet teeth; and means also carried by the rotatable structure for controlling the 75 operation of the dog.

In witness whereof I affix my signature. 85
ADOLPH W. SCHRAMM.
